Primary Examiner—Ian Simmons*Assistant Examiner*—Charles D Hanson(74) *Attorney, Agent, or Firm*—Polster Lieder Woodruff & Lucchessi, LC(57) **CLAIM**

The ornamental design for a dental cabinet, as shown and described.

DESCRIPTION

FIG. 1 is a front perspective view of the dental cabinet;

FIG. 2 is a front view thereof;

FIG. 3 is a right side view thereof;

FIG. 4 is a back view thereof;

FIG. 5 is a left side view thereof;

FIG. 6 is a top view thereof; and,

FIG. 7 is a bottom view thereof.

The broken lines are included for the purpose of illustrating environmental structure and form no part of the claimed design.
